INVENTOR

BY *Victor J. Evans*

ATTORNEY

UNITED STATES PATENT OFFICE.

JOHN ELLIOTT COWEL, OF CREST, COLORADO.

MEANS FOR CONNECTING STOVEPIPE SECTIONS.

Application filed February 7, 1921. Serial No. 443,147.

To all whom it may concern:

Be it known that I, JOHN ELLIOTT COWEL, a citizen of the United States, residing at Crest, in the county of Weld and State of Colorado, have invented new and useful Improvements in Means for Connecting Stovepipe Sections, of which the following is a specification.

My present invention has reference to means for connecting stove pipe sections for supporting the same in longitudinal alignment.

My object is to produce a simple means for accomplishing this purpose comprising a hooked member carried by and projecting outward from one of the pipe sections and designed to be engaged by a spring jaw carried by the other section.

A further object is to produce means for connecting the sections of a stove pipe comprising interengaging spring elements carried by both of the sections which snap into engagement when brought together and which effectively hold the sections against either outward or inward longitudinal movement and also prevent accidental turning of one of the sections on the other, but permitting such turning when manual force is employed so that the interengaging means may be brought away from each other and the sections thus readily disassembled.

The foregoing, and other objects which will appear as the nature of the invention is better understood, may be accomplished by a construction, combination and operative arrangement of parts, such as is disclosed by the drawings which accompany and which form part of this application.

In the drawings:—

Figure 1 is an approximately central longitudinal sectional view through a stove pipe section connected to a thimble in accordance with this invention.

Figure 2 is a perspective view of the jaw member which is secured to one of the pipe sections.

Figure 3 is a similar view of the hook member which is secured to the other pipe section.

While it is to be understood that the improvement is employed for connecting stove pipe sections to hold the same in alignment,

I have, in Figure 1 of the drawings, shown one of the pipe sections 1 in the nature of a thimble, and has its inner edge flanged to 55 contact with the inner wall of the chimney, while the same is formed with bendable lugs 2 to contact with the outer face of the chimney, thus holding the thimble against longitudinal movement through the pipe opening.

Secured in the socket end 5 of a pipe section 6 are flat metal straps 3. Each of the straps has its end which projects through the 65 socket 5 bent upon itself to provide the same with a hook 4.

In the thimble 1 there are secured flat metal straps 5' each of which having its outer end bent to provide a hook 7'. Each 70 strap 5' is approximately centrally bent upon itself, so that each strap is formed with an overlying portion 6', which projects a suitable distance beyond the hook 7'. This projecting end is curved by virtue of its 75 contact with the hook, the said curved end being indicated by the numeral 8.

The strips 3 and 5' being constructed of metal are naturally resilient, and when the mouth 5 of the pipe section 6 is inserted in 80 the thimble 1, the said pipe section is given a turn to bring the hook 4 of the strips 3 beneath the flared portions 8 of the outer members 6' of the strips 5' and in engagement with the hook 7' on the ends of the 85 said strips. The portions 8 are in the nature of spring jaws and exert a tension 90 against the hooks 4 of the strips 3, holding the said hooks 4 in engagement with the hooks 7', and thus sustain the pipe sections 6 90 in proper longitudinal alignment with the thimble 1.

Having described the invention, I claim:—

The combination with two stove pipe sections, one having resilient strips with a 95 hook at their outer ends projecting out of one end of the said section, the other having straps with a hooked end engaging the hooked end projecting from the first mentioned section, and a resilient strip bearing 100 on each pair of locked hooks for holding the same in engagement.

In testimony whereof I affix my signature.

JOHN ELLIOTT COWEL.
